UNITED STATES PATENT OFFICE.

GEORGE L. IZARD, OF MOBILE, ALABAMA.

MEANS FOR TREATING THE EAR.

Application filed October 11, 1922. Serial No. 593,930.

To all whom it may concern:

Be it known that I, GEORGE L. IZARD, a citizen of the United States, residing at Mobile, in the county of Mobile and State 5 of Alabama, have invented certain new and useful Improvements in Means for Treating the Ear; and I do hereby declare the following to be a full, clear, and exact description of the invention, such as will enable 10 others skilled in the art to which it appertains to make and use the same.

This invention relates to treatment of the ear for the purpose of improving the sense 15 of hearing of persons suffering from deafness and ameliorating the annoying conditions commonly associated with abnormal conditions of the organs of hearing.

It consists in simultaneously treating the 20 organs of hearing with vibrations associated with sounds, and with remedial fluids, such as dry hot air or the warm vapor of a suitable medicament, whereby the organs may respond mechanically to the vibrations of sound while being massaged, as it were, by 25 said vibrations, thus receiving the beneficial effects of approved remedial fluids while being massaged; it further consists in an instrumentality for applying the treatment, comprising the combination of sound producers 30 and remedial fluid generating or conditioning means whereby the sound vibrations may be transmitted to the ear simultaneously with the application of remedial fluid through the same conductors; it further 35 consists in the specific treatment and means of treatment more particularly described hereinafter, illustrated in the drawings and defined in the appended claims.

In the drawings I have illustrated a preferred embodiment of my invention and have indicated like parts by like reference characters throughout.

In said drawings,—

Figure 1 is a plan view of the base portion of the instrumentality;

Figure 2 is a side elevation of the base portion showing, mounted thereon, a hollow collecting and conducting body in vertical section.

Figure 3 is an elevation of the apparatus shown in Figure 2 viewed from a position at right angles to the position from which the apparatus is viewed in Figure 2 and

showing the hollow collecting and conducting body in section on a plane disposed at 55 an angle of 90° with respect to the plane of the section illustrated in Figure 2.

In the drawings, A represents the base of the instrumentality adapted to support 60 all parts thereof and B represents a hollow collecting and conducting member removably seated on said base.

The base A may be of any suitable form and material. The base shown in the drawing is of rectangular form in plan and of suitable thickness. It may be made of wood or any other substance suitable for the purpose. Rising from said base nearer what I term the rear portion than the front portion thereof is a support 1 of any suitable form, but preferably cylindrical, having a central platform or seat 2 which may be slightly depressed below the top. This support may also be of wood or other material suitable for the purpose. Mounted on said support 1 is a cluster or series of sound producing devices which may be, as shown, electrically operated and in the nature of electric bells or buzzers. In the embodiment illustrated, there are six of such devices designated respectively by the reference characters 3, 4, 5, 6, 7 and 8. The sounding device 3 is preferably what is known as a buzzer or similar device having a low degree of resonance. The devices 4, 5, 6, 7 and 8 are preferably 65 gongs adapted to produce tones or sounds of different pitch, or sound vibrations of different frequency and amplitude. The said sounding devices have associated with them suitable electric circuits well understood and not necessary to be illustrated in detail. The said circuits are arranged in two groups—in the embodiment shown, of three each. Each group of circuits may be controlled by a triple knife switch indicated 70 at 9 and 10, whereby three of the sounding devices may be energized or de-energized at will as a group. Each sounding device circuit is also individually controlled by an individual switch or push button as indicated at 11 and 12. In the front of the base or at any other suitable point there may be a terminal socket a in which conductors or 75 circuits mounted in the base terminate and which may be connected to a duplex conductor cord for connecting the apparatus 80 to an electrical circuit.

with a lamp socket or other terminals of a source of electrical energy. It will thus be seen that the sounding devices may be de-energized in groups, that any one of them 5 may be individually energized or that any combination of them may be energized at will.

A plug 13 may also be mounted on the base so that connection may be made there-10 with to a suitable heater 14 or 15, according to the method of treatment to be adopted. The heater 14 illustrated in Figure 2 may be a standard electrical resistance immersion heater, the coil of which may be immersed 15 in liquid carried in a suitable container or tumbler, such as is indicated at 16, resting upon the platform 2 of the support 1. It is preferred that the container 16 be made of metal, but this is not material. By means 20 of the heater 14 a suitable liquid medicament contained in the vessel 16 may be heated. It will be understood that said heater may be provided with any usual switch device 14^a, to make or break the circuit when 25 it is coupled to the plug 13.

The heater 15 is of such design that it may rest upon the platform 2 when the container 16 is removed. The heater 15 is intended 30 to be coupled to the socket 13 when it is desired to obtain dry hot air for treating the organs of hearing.

The collecting and conducting body B may be made of metal and is preferably of conoidal form open at both ends, the larger 35 end being of such size as to rest upon the base A and enclose the previously described support 1 with the sounding devices mounted thereon, the container and heater 14, or the heater 15 when said container is not in 40 use. The opening 17 at the apex of the conoidal body is of such size as to emit the sound waves and aeriform currents generated in the body B in condensed state so as to be concentrated at or near the outer 45 ear of a patient holding his head over said opening. Preferably also, but not necessarily, there may be an opening 18 in one side of the conoidal body with which a flexible tube 19 communicates, having a nozzle 50 20 of convenient size and form to be inserted in one of the nostrils of a patient. By reason of this construction the patient may be treated with the sound vibrations and remedial aeriform fluid simultaneously 55 through the outer ear which may be held over the opening 17, while at the same time medicated vapors or heated air may be carried to the inner ear through the nostril by means of the tube 19 and nozzle 20. The 60 method of treatment may be as follows:—

The hollow collecting body B is seated in place, the patient places his ear adjacent to the opening 17, the operator may then close 65 the circuits of selected sounding devices and test the hearing of the patient. He may also

vigorously massage the organs of hearing by operating all of the sounding devices at one time. Should the operator deem it advisable to apply a vaporous medicament to the patient, he will fill the container 16 with the liquid medicament, couple the heater 14 inserted in the medicament, turn on the current and boil the liquid. Now the medicated vapor is issuing from the orifice 17 and the nozzle 20 and may thus be applied 70 to the external and internal ear of the patient. At the same time that medicament is being applied, the operator will cause sound waves to be transmitted to the organs of hearing by manipulating the push buttons 75 11 and 12 in connection with the switches 9 and 10. He may, if conditions warrant, massage the organs by sound waves transmitted from a particular selected sound producer, such as previous tests of the patient 80 indicate the patient hears less distinctly than others. Should treatment with heated air instead of medicated vapors be indicated, container 8 and heater 14 may be removed 85 and the dry air heater 15 substituted for it, the treatment then continuing somewhat 90 as before indicated.

It is my belief that the concentrated sound vibrations transmitted to the ear simultaneously with medicated vapor or dry hot air have a direct beneficial effect upon the tympanic membrane, the ossicles of the middle ear, the rods of Corti and, in fact, upon all 95 of the organs of hearing which are reached by the aeriform fluid while being stimulated by the sound waves. It is my belief that the stimulating effect of this combined treatment increases the circulation of blood to the organs of hearing and tends to cause 100 the organs to respond more naturally to transmitted sounds. But, whatever may be the theory of the reaction of the organs to this treatment, I have found by experience 105 that cases of progressive deafness of long standing have yielded to treatment to such an extent that the sense of hearing has been partially restored and the patient relieved of troublesome noises and other symptoms to which the partially deaf are subject. 110

What I claim and desire to secure by Letters Patent is:—

1. In an instrumentality for treating the organs of hearing, means for producing sounds, a hollow body adapted to collect the sound waves and direct them to the organs of hearing, and means whereby a remedial aeriform fluid may be conducted through said hollow body with said sound vibrations to the ear. 120

2. In an instrumentality for treating the organs of hearing, means for producing sounds, a hollow body inclosing said sound producing means, said hollow body having an outlet for directing the sound vibrations 125 to the organs of hearing, and means within 130

said hollow body for conditioning a remedial aeriform fluid and applying it through said outlet to the ear.

3. In an instrumentality for treating the 5 organs of hearing, means for producing sounds, a conoidal hollow body having an opening in its apex, for enclosing said sound producing means, and means within said conoidal body for conditioning a remedial 10 aeriform fluid.

4. In an instrumentality for treating the organs of hearing, means for producing sounds, a hollow body inclosing said sound producing means, said hollow body having 15 two openings, a flexible tube connected at one of said openings, and means within said body for conditioning a remedial aeriform fluid.

5. In an instrumentality of the class de- 20 scribed, a base, a plurality of sound producing devices adapted to produce a continuous succession of sounds of different pitch and intensity singly or in unison, control devices of such character that the sound pro- 25 ducing devices may be operated selectively or in any desired combination, and a cone shaped body disposed over said sound producing devices and having its larger end se- cured to said base.

30 6. In an instrumentality of the class de- scribed, a base, a support rising therefrom, a plurality of sound producing devices dis- posed on and around said support, thereby providing a central platform for receiving

a fluid heating device, and controlling means 35 for said sound producing and fluid heating devices.

7. In an instrumentality for treating the organs of hearing, a base, a support rising therefrom, a plurality of electrically op- 40 erated sound producing devices disposed on and around said support, circuits therefor, a plurality of circuit closing devices adapted to open or close groups of said circuits, an individual circuit closing device for the cir- 45 circuit of each sound producing device, and a cone shaped body disposed over said support and the sound producing devices at- tached thereto, said cone shaped body hav- 50 ing its larger end secured to said base.

8. In an instrumentality of the class de- scribed, a base, a support rising therefrom, a plurality of electrically operated sound 55 producing devices disposed on and around said support and circuits therefor, an elec- trical fluid heating device, adapted to rest upon said support and a circuit therefor, a hollow conoidal body adapted to inclose said sound producing device and heating device, 60 said hollow body having openings for direct- ing sound vibrations and heated aeriform fluid to the organs of hearing, and circuit controlling devices in said base of such character that the sound producing devices 65 may be operated selectively or in groups.

In testimony whereof I affix my signature.

GEORGE L. IZARD.
